CLAIM

The ornamental design for an instant photo print, as shown and described.

DESCRIPTION

FIG. 1 is a top, front and left side perspective view of an instant photo print showing my new design;

FIG. 2 is a front elevational view thereof;

FIG. 3 is a rear elevational view thereof;

FIG. 4 is a top plan view thereof;

FIG. 5 is a left side elevational view thereof; and,

FIG. 6 is a front elevational view thereof in a manner of use. The broken lines in the drawings depict environmental subject matter only and form no part of the claimed design.

The shaded areas in the figures depict contrast.
